UNITED STATES PATENT OFFICE.

WESLEY P. HEISNER AND PAUL A. HEISNER, OF ROCKVILLE, NEBRASKA.

ADJUSTABLE STRAINER SUPPORT.

Application filed May 31, 1922. Serial No. 564,911.

To all whom it may concern:

Be it known that WESLEY P. HEISNER and PAUL A. HEISNER, citizens of the United States, residing at Rockville, in the county 5 of Sherman and State of Nebraska, have invented certain new and useful Improvements in Adjustable Strainer Supports, of which the following is a specification, reference being had therein to the accompanying drawings.

The invention relates to adjustable strainer supports and has for its object to provide a device of this character comprising a strainer supporting ring formed from 15 hingedly connected semi-circular sections hingedly movable in the same plane and provided with outwardly extending arms slidably and hingedly mounted on the ring sections and forming means for supporting the 20 ring over a separator or other receptacle for supporting a strainer.

A further object is to provide an extensible arm carried by one of the supporting arms and forming means whereby the support may be supported on various sizes of 25 separators or receptacles.

A further object is to provide means whereby the strainer supporting ring may be adjusted for receiving different sizes of 30 strainers.

With the above and other objects in view the invention resides in the combination and arrangement of parts as hereinafter set forth, shown in the drawings, described and 35 claimed, it being understood that changes in the precise embodiment of the invention may be made within the scope of what is claimed without departing from the spirit of the invention.

40 In the drawings:

Figure 1 is a top plan view of the strainer supporter.

Figure 2 is a longitudinal sectional view through the supporter.

45 Referring to the drawings, the numeral 1 designates a ring in which a conventional form of strainer, for instance of the tapered type is supported above a separator or other receptacle. The ring 1 comprises two seg- 50 mentally shaped sections 2, which are hingedly connected together at 3 in such a manner that the sections may move independently of each other in the same plane, thereby allowing the ring to be extended in size 55 and held in adjusted position by means of the set screw 4 which passes through the

outer wall of the sleeve 5 which is secured at 6 to one of the sections 2 and in the flared chamber 7 of which the end 8 of the other section may move. Slidably mounted on the 60 ring sections 2 are sleeves 9, which sleeves frictionally engage the sections 2 and will stay in any position to which they may be moved and thereby allowing the sleeve to be 65 diametrically positioned according to the position of the ring sections 2 when adjusted outwardly, and consequently the device to balance when on a receptacle 10. Hingedly connected at 11 to the sleeves 9 adjacent their lower sides are receptacle engaging 70 arms 12 and 13. The arm 12 is provided with a flange 14 which engages the outer side of the receptacle 10 and is held in close engagement therewith by means hereinafter set forth in such a manner as to prevent easy 75 tipping of the device. Each arm 12 and 13 is provided with a vertically disposed portion 15 which engages the outer sides of the sleeves 9 and prevents collapsing of the device when on a receptacle. However by 80 providing the hinging points 11 adjacent the lower sides of the sleeves 9, the arms 12 and 13 may be folded downwardly onto the ring and onto each other in such a manner as to 85 form a compact structure for storage purposes. The arm 13 is provided with an elongated slot 16, through which slot the rectangular portion 17 of a threaded lug 18 passes, and on which threaded lug a thumb nut 19 is threaded. It will be seen that when 90 the thumb nut 19 is loosened that the extension arm 20 may be adjusted outwardly or inwardly and held in adjusted position, thereby allowing the flange 21 of the arm 20 to be held in close engagement with the 95 outer wall of the receptacle 10 and also the flange 14 of the arm 12 in close engagement with the receptacle in such a manner as to frictionally bind and prevent tilting of the device as a whole when supporting a 100 strainer.

From the above it will be seen that a strainer support is provided, which support is simple in construction, the parts reduced to a minimum, and one which may 105 be easily and cheaply constructed.

The invention having been set forth what is claimed as new and useful is:—

A strainer supporter comprising a strainer receiving ring, said ring comprising hingedly connected ring sections movable in the same plane, a sleeve carried by 110

one end of one of the sections and having a tapering chamber therein for the reception of the adjacent end of the adjacent section, set screw means for holding the ring sections in adjusted positions, sleeves slidably mounted on the ring sections, upwardly and outwardly extending arms hingedly connected to the sleeves adjacent their lower sides and in abutting engagement with the sleeves, one of said arms being provided with

an outwardly and inwardly adjustable arm, downwardly extending flanges carried by the adjustable arm and the upwardly and outwardly extending arm and forming means for frictionally engaging opposite sides of a receptacle. 15

In testimony whereof we hereunto affix our signatures.

W. P. HEISNER.
